UNITED STATES PATENT OFFICE.

HARRY A. BREMER, OF CHICAGO, ILLINOIS, ASSIGNOR TO BREMER-TULLY MANUFACTURING COMPANY, OF CHICAGO, ILLINOIS, A CORPORATION OF ILLINOIS.

SYSTEM OF RADIOPHONIC COMMUNICATION.

Application filed December 1, 1924. Serial No. 753,147.

To all whom it may concern:

Be it known that I, HARRY A. BREMER, a citizen of the United States, residing at Chicago, in the county of Cook and the 5 State of Illinois, have invented a certain new and useful Improvement in Systems of Radiocommunication, of which the following is a full, clear, concise, and exact description.

10 My invention relates to radio communication and resides in the provision of improved means for compensating for or offsetting undesired feed back effects.

It is well known that resonant thermionic valve input and output circuits of low resistance are desirable for the best operation of an amplifying thermionic valve. However, the bringing of the output circuit into resonance with the input circuit 20 of such a valve tends to produce oscillation. Decreasing the resistance of the input circuit also tends to favor oscillation. In order to secure the advantages of low resistance tuned circuits, it is necessary to 25 employ some means for preventing or controlling oscillation. Methods now employed for this purpose require considerable readjustment for changes in frequency or wave lengths or fail when the resistances of the circuits are reduced to a low 30 value.

The system of my invention employs a bridge connecting the input and output circuits of a thermionic valve and including 35 means serving to oppose the feed back effect of the output circuit upon the input circuit. In the preferred embodiment of the invention, I employ an input transformer having a secondary in the input circuit, an output transformer having a primary in the output circuit, two coils in the bridge, one being in inductive relation to 40 said input transformer secondary and serving to oppose the feed back effect of the 45 output circuit on the input circuit and the other being in inductive relation to said output transformer primary and furnishing a compensating feed back effect, and adjustable capacitance in said bridge.

50 The invention will be more fully explained in connection with the accompanying drawing which is a diagrammatic illustration of the preferred embodiment thereof.

55 Radio frequency current traverses the aerial 1 and the transformer primary 2,

to ground 3. The secondary 4 of the coupler and the variable secondary tuning condenser 5 in shunt relation thereto, are also traversed by radio frequency current. The radio frequency amplifying tube or thermionic valve 6 includes a grid 7 that is connected with one terminal of each of the elements 4 and 5. The plate or electrode 8 of this valve receives and imparts current of amplified radio frequency, there being the usual heating filament 9 whose effect is regulated by means of the rheostat 10 which is in a local circuit with the filament of the A battery or other source of current 11. The B battery 12 supplies voltage to the valve electrode 8.

The valve 6 has an output circuit commencing at its electrode 8 which has in series therewith the primary 13 of an air core radio frequency transformer. A secondary 14 that is individual to the primary 13 supplies amplified radio frequency current to a circuit which includes the grid 15 of the thermionic valve 16, there being a variable condenser 17 included in a bridge 18 between the sides of the secondary circuit containing the winding 14. The thermionic valve 16 includes the usual heating filament 18 in a local circuit with the A battery 11 and the rheostat 19 which controls the heating effect of this filament. Current is received by the plate or electrode 20 of the valve 16 and is supplied to the primary 21 of an air core transformer, the secondary 22 of this transformer supplying audio frequency current to the input grid 23 of a rectifying thermionic valve 24 by way of the condenser 25 which is bridged by a leak 26. Valve 24 includes the usual heating filament 28 whose effect is controlled by the usual rheostat 29. The secondary 22 is shunted by a variable condenser 27. The rectified audio frequency current is received by the plate or electrode 30 and is supplied to the telephone or other receiver 31.

A bridge 32 (shown by heavy lines for clearness) is connected at one end between the plate 20 of the valve 16 and the primary 21 which is connected with this plate. The other end of this bridge is connected with the end of the secondary 14 which is connected with the filament 18. The bridge includes two coils 33, 34 that are respectively inductively related to the coils 14 and 21. A variable coupler in the form of

adjustable capacitance 35 is included in the bridge between the coils 33 and 34.

The inductive relation of coil 33 to coil 14 is such as to oppose the feed back effects of the output circuit on the input circuit of the valve 16.

The combined direct plate potential and inductive action of coil 21 on coil 34 tends to produce a compensating feed back which when coupled inductively to coil 14 through coil 33 permits operation of the valve just below the point of oscillation over a large variation of frequency without readjustment of the control. Adjustment of feed back is secured by means of the variable condenser 35 which acts as a variable coupling between coil 33 and the coils 21, 34.

The compensating coil 34 tends to correct the variation of adjustment for various wave lengths.

In an equipment lacking my invention, the receiver may be adjusted by condenser 35 so that it becomes sensitive at short wave lengths, as two hundred and twenty meters. Considerable readjustment of condenser 35 is necessary at five-hundred meters to bring the tube back to the same sensitivity. By employing the coil 34 as set forth, it is possible to maintain the sensitivity of the circuit from two hundred to five hundred meters, for example, with only very slight adjustment of condenser 35. If this condenser is given a permanent adjustment at a wave length of, say, two hundred and twenty meters, the circuit will be much more sensitive at five hundred meters, for example, than if the prior method were used.

By "sensitivity" is meant just below and remaining at the point of oscillation for the tube for a considerable range of wave lengths, a condition realized by the compensating action of the coil 34.

Adjustment is required as wave lengths vary because capacity and inductive effects vary considerably as wave lengths vary. Coil 34, when close coupled to the plate coil 21 and connected in the plate shunt circuit, as shown, compensates for this variation.

Changes may be made without departing from my invention.

Having thus described my invention, I claim:

1. In a radio system of communication, the combination with a thermionic valve having an input circuit and an output cir-

cuit; of an input transformer having a secondary in said input circuit; an output transformer having a primary in said output circuit; a bridge connecting said circuits and including two coils, one being in inductive relation to the said input transformer secondary and the other being in inductive relation to said output transformer primary, the first coil operating through the input transformer secondary to oppose the feed back effect of the output circuit upon the input circuit and the second coil deriving potential from the output transformer primary and supplying it to the first coil for this purpose; and adjustable capacitance in said bridge.

2. In a radio system of communication, the combination with a thermionic valve having an input circuit and an output circuit; of an input transformer having a secondary in said input circuit; an output transformer having a primary in said output circuit; a bridge connecting said circuits and including two coils, one being in inductive relation to the said input transformer secondary and the other being in inductive relation to said output transformer primary, the first coil operating through the input transformer secondary to oppose the feed back effect of the output circuit upon the input circuit and the second coil deriving potential from the output transformer primary and supplying it to the first coil for this purpose; and a variable coupling between the coils in said bridge.

3. In a radio system of communication, the combination with a thermionic valve having an input circuit and an output circuit; of an input transformer having a secondary in said input circuit; an output transformer having a primary in said output circuit; and a bridge connecting said circuits and including two coils, one being in inductive relation to the said input transformer secondary and the other being in inductive relation to said output transformer primary, the first coil operating through the input transformer secondary to oppose the feed back effect of the output circuit upon the input circuit and the second coil deriving potential from the output transformer primary and supplying it to the first coil for this purpose.

In witness whereof, I hereunto subscribe my name.

HARRY A. BREMER.
